(57) **CLAIM**

(21) Appl. No.: **29/352,027**

I claim the ornamental design of a gastric bypass medical alert device, as shown and described.

(22) Filed: **Dec. 15, 2009**

DESCRIPTION

(51) **LOC (9) Cl.** **11-03**

FIG. 1 is a perspective view showing my gastric bypass medical alert device.

(52) **U.S. Cl.** **D11/102; D11/116**

FIG. 2 is a front elevation view showing my gastric bypass medical alert device.

(58) **Field of Classification Search** D11/1-2,

FIG. 3 is a top plan view showing my gastric bypass medical alert device.

D11/40-41, 43-50, 53, 56, 60, 63, 65, 67,
D11/75-78.1, 86, 89, 95-105, 108-109, 115-116,
D11/81, 54, 61, 79; 63/1.11, 1.12, 1.13,
63/1.14, 1.16, 1.18, 13, 14.1, 35, 38, 39

FIG. 4 is a left side elevation view showing the left side portion of my gastric bypass medical alert device.

See application file for complete search history.

FIG. 5 is a rear elevation view showing my gastric bypass medical alert device.

(56) **References Cited**

FIG. 6 is a right elevation view showing my gastric bypass medical alert device; and,

U.S. PATENT DOCUMENTS

FIG. 7 is a bottom plan view showing my gastric bypass medical alert device.
